UNITED STATES PATENT OFFICE.

DAVID GREENE-HASKINS, OF CAMBRIDGE, MASSACHUSETTS.

SCREW-PROPELLER.

SPECIFICATION forming part of Letters Patent No. 224,289, dated February 10, 1880.

Application filed June 12, 1879.

To all whom it may concern:

Be it known that I, DAVID GREENE HAS-
KINS, of Cambridge, in the county of Middle-
sex and State of Massachusetts, have invented
5 a new and useful Improvement in Screw-Pro-
pellers, of which the following is a specifica-
tion.

The object of my invention is to provide a
means for increasing the power and effective-
ness of screw-propellers, especially in prevent-
ing the loss from slip.

My invention consists in the employment,
instead of single blades, upon the propeller-
shaft, of groups of blades, each blade of the
15 group being arranged one nearly in front of
the other, and increasing progressively in
length and width from the front blade, which
is the smallest, to the rearmost blade, which is
the largest. The blades in each group are so
20 arranged relatively that as the propeller rotates
the advancing edge of the rearmost or
largest blade shall cut the water first and be
followed successively by each of the other
blades of the group to the foremost or small-
25 est blade, which cuts the water last.

Referring to the drawings, Figure 1 repre-
sents a front view of a propeller embodying
my invention. Fig. 2 is a side or end view of
the same.

30 A B C represent a group of three blades,
there being represented three such groups
upon the shaft. A A A are the rearmost and
largest blades, which may be cast with or form
a part of a central bearing, F, journaled upon
35 the shaft D.

In front of the blades A are placed the
blades B B B, which are of less length and
width than the blades A, as shown, and hav-
ing their radial advancing edges at an angle
40 with those of the blades A.

In front of the blades B are arranged the
blades C C C, of less length and width than
the blades B, and having their radial advanc-
ing edges at an angle with those of the blades B.

45 The rotation of the blades is in the direc-
tion indicated by the arrow, so that the blades
A will cut the water first and be followed suc-
cessively by the blades B and C.

By this construction and arrangement of the
50 blades the water, as the vessel advances, is
caught by the projecting portions of the sev-

eral blades and turned into the spaces be-
tween the same, where the force and reaction
of the water serve to impart the greatest
efficiency to the propeller and prevent slip. 55

By making the blades of the several groups
of unequal length, increasing from the front
to the rearmost blade, that portion of each
blade where its leverage to turn the propeller
is greatest is exposed to the direct action of 60
the water, which also, as the wheel advances,
reacts advantageously upon the face of the
blade in front.

The water passing through the spaces be-
tween the blades is thrown off at right angles 65
to the direction of the shaft, thus obviating
the objection occasioned by tail-water to the
use of more than one propeller placed near
another upon the same shaft.

As another advantage of my improved con-
struction, propellers of comparatively small
70 diameter will have equal power with those of
much larger diameter constructed in the usual
manner.

The blades B C may be attached to a blade, 75
A, representing that of any propeller, by
means of rivets or otherwise, at a point near
its connection with the shaft.

I have described a propeller as composed
of three groups of blades; but two groups may 80
be sufficient, and more than three may be used.

What I claim as my invention is—

1. A propeller composed of two or more
groups of blades, each blade of each group
differing in size, and each diminishing in size 85
from the rear to the front blade, substantially
as specified.

2. A propeller composed of groups of blades
of unequal length and width, in which the
blades of each group are so arranged that the 90
advancing edges of the several blades of each
group shall strike the water in succession, the
edges of the rearmost blades cutting the water
first and those of the front blades cutting the
water last, substantially as set forth. 95

In testimony whereof I have signed my name
to this specification in the presence of two sub-
scribing witnesses.

DAVID GREENE HASKINS.
